UNITED STATES PATENT OFFICE

OTTO M. SUMMERS, OF DAYTON, OHIO, ASSIGNOR TO FRIGIDAIRE CORPORATION, OF DAYTON, OHIO, A CORPORATION OF DELAWARE

REFRIGERATING APPARATUS

Application filed November 30, 1928. Serial No. 322,748.

This invention relates to refrigerating apparatus and particularly to an improved construction of evaporators for such apparatus.

One of the objects of the invention is to provide an improved evaporator construction which is simple and economical to build, and which is lighter than those heretofore used without sacrificing sturdiness or strength.

Another object is to provide an improved form of joint between a header or container and a removable closure therefor.

More specifically it is an object of the invention to provide an improved connection between the header and removable cover which will effectively prevent water from freezing between the header and the cover.

Still another object is to provide an improved construction which does not depend upon soldering or welding to form either a mechanical connection or a fluid seal between parts.

Further objects and advantages of the present invention will be apparent from the following description, reference being had to the accompanying drawings, wherein a preferred form of the present invention is clearly shown.

In the drawings:

Fig. 1 is a vertical longitudinal section of a portion of a refrigerating evaporator embodying the invention;

Fig. 2 is an end elevation of the same;

Fig. 3 is a section on the line 3—3 of Fig. 1 and Fig. 4 is a sectional view of a gasket corresponding to Fig. 1.

Refrigerating evaporators including a header forming a reservoir for liquid refrigerant, a number of loops of tubing joined to the header for circulating refrigerant, and a removable closure plate for the header carrying a float-control valve for regulating a quantity of liquid refrigerant in the evaporator, have heretofore been made, an example of such general construction being shown in my application Serial No. 266,397 filed March 31, 1928. It has been the custom to construct the headers of these evaporators of a drawn metal shell usually of brass. Because the closure plate carries a number of quite heavy valves, its construction must be

necessarily heavy, and because this heavy assembly of plate and valves must be removably secured to the thin sheet metal shell it is necessary to provide a very substantial anchoring device to which the plate may be secured. It has been customary to form this anchoring device as a heavy forged brass ring which is soldered in the end of the shell and provided with tapped holes for receiving bolts for securing the plate in place. This type of construction has necessarily resulted in an extremely heavy evaporator and one which has been expensive to manufacture. Another undesirable feature of evaporators of this type is that the soldered connection of the shell to the ring is subject in certain instances to electrolytic decomposition. Furthermore it has been found that during operation water will condense on the evaporator and collect in the crevice between the plate and the ring outside of the usual sealing gasket. This water freezes in the crevice and damages the evaporator.

My invention is concerned among other things with overcoming the above mentioned disadvantages in prior constructions.

Referring to the drawings 10 designates a sheet metal shell forming the main body of the header to which are connected a number of tubes 11 for circulating refrigerant. The particular method of connecting the tubes is not shown herein but a solderless mechanical connection is preferred such as is shown in my application for refrigerating apparatus executed November 28, 1928 (docket F-1927). The open end of the shell or body of the header is formed into a flange 12 which projects inwardly substantially at right angles to the cylindrical wall. Within the header and before the flange is formed is placed a ring 14 which fits against the wall of the header and the flange and is provided with openings 15 tapped to receive bolts as will be explained below. The ring may be loose within the header or for purposes of convenience may be soldered to the flange. The ring is of rigid inexpensive material such as a steel punching.

A cover or closure for the header includes a plate forming a reinforcing member which

likewise is of rigid, inexpensive material, for example, a steel punching 16, and a cover plate 17 enclosing the reinforcing member and preferably formed of the same material 5 as the header, for example soft brass. The cover plate is rolled or otherwise suitably formed so as to enclose the reinforcing member as shown in Fig. 1 and to provide a plane flange 18 projecting inwardly from its edge 10 and corresponding to the flange 12. The reinforcing member and plate are pierced with openings 19 which register with the holes 15 in the ring 14 for receiving clamping bolts 20. The clamping bolts are threaded into 15 the openings 15 and project through the cover. Screw-threaded caps 22 are threaded on to the ends of the bolts. A gasket 24 is placed between the flanges outside of the bolts for facilitating the sealing together of 20 the flanges. This gasket preferably is of the same material as the shell and cover plate, that is, soft brass, and includes a bead of such diameter that it fits substantially the outside edges of the flanges, leaving no 25 appreciable crevice between them. The bead is provided with an inwardly extending web 26 of such internal diameter as to engage the bolts and accurately center the bead with respect to the flanges. The screw 30 caps are formed of the same material as the cover plate and are provided with relatively sharp edges 28. When the caps are screwed down tight the cover is clamped securely to the container, the gasket, bead and flanges 35 being of such material as to flow into sealing engagement with each other under the force exerted by the bolts and the edges of the caps flowing into sealing engagement with the cover plate. Thus the container is sealed 40 gas-tight by the gasket and screw caps.

The cover is provided with openings 30 and 31 for communicating with inlet and outlet conduits respectively. Conduit connections in the form of an inlet valve casing 45 32 and an outlet valve casing 33 abut the cover plate opposite these openings, and preferably have centering bosses 35 which fit into the holes 30 and 31. These casings are constructed of soft brass and are provided 50 with sharp sealing edges 36. Between the valve casings a bolt 38 is threaded into the reinforcing member 16 and is preferably sweated into the cover plate 17 with solder, such solder forming a gas-tight connection 55 and being disposed within the body of the container or cover where it cannot come in contact with condensing water and thus is secure from electrolytic decomposition. A clamping plate 39 which engages both valve 60 casings is urged toward the cover by a nut 40. The bolt, nut and clamping plate form a single clamping means which secures both valve casings to the plate with sufficient force to cause the edges 36 to flow into sealing engagement with the plate.

A boss 42 is screwed and soldered to the inside of the reinforcing member opposite the inlet opening 30. This boss is hollow to permit refrigerant to flow into the header. A sleeve 44 carrying an arm 45 surrounds the boss and is secured thereto by screws 46. The sleeve has an opening 47 which forms a guide for a needle valve 48 carried by one arm 49 of a bell-crank lever pivoted to the arm 45, the other arm 50 of the bell-crank lever carrying a float ball for actuating the needle valve. The needle valve seats in the opening in the end of the boss 47 and regulates the quantity of liquid in the header. 70

A vapor withdrawing tube 53 is secured 80 to the reinforcing member 16 in the outlet opening 31 and projects into the header and above the level of the liquid therein.

While the form of embodiment of the invention as herein disclosed, constitutes a preferred form, it is to be understood that other forms might be adopted, all coming within the scope of the claims which follow. 85

What is claimed is as follows:

1. In an evaporator for refrigerating apparatus, a cylindrical container forming a reservoir for liquid refrigerant having a flange formed out of the body of the container and projecting substantially at right angles to the axis of the container, a ring 90 within the container adjacent the flange, a closure for the container, tension means engaging the closure and ring to clamp the closure to the flange, and a gasket between said flange and said closure, said gasket including a bead and an inwardly extending web, said web being adapted to engage the tension means to space the bead substantially at the outer edge of said flange. 95

2. In an evaporator for refrigerating apparatus, a cylindrical container forming a reservoir for liquid refrigerant having a flange formed out of the body of the container and projecting substantially at right angles to the axis of the container, a ring 105 within the container adjacent the flange, a closure for the container having openings therethrough, tension members engaging the ring and passing through said openings for clamping the closure to the flange, and means 110 for sealing the free ends of the tension members. 115

3. In an evaporator for refrigerating apparatus, a cylindrical container forming a reservoir for liquid refrigerant having a flange formed out of the body of the container and projecting substantially at right angles to the axis of the container, a ring 120 within the container adjacent the flange, a closure for the container having openings therethrough, tension members engaging the ring and passing through said openings for clamping the closure to the flange, means for sealing the openings around the tension members, and a gasket of material of substan- 125

- tially the same hardness and plastic qualities as the container and closure disposed between the flange and the closure outside of the tension members.
5. 4. In an evaporator for refrigerating apparatus, a cylindrical container forming a reservoir for liquid refrigerant having a flange formed out of the body of the container and projecting substantially at right angles to the axis of the container, a ring within the container adjacent the flange, a closure for the container having openings therethrough, tension members engaging the ring and passing through said openings for 10 clamping the closure to the flange, and sealing means for the openings comprising screw-threaded caps for the tension members, said caps being adapted to engage the closure with a sealing contact around the tension members.
15. 5. In an evaporator for refrigerating apparatus, a cylindrical container forming a reservoir for liquid refrigerant having a flange formed out of the body of the container and projecting substantially at right angles to the axis of the container, a ring within the container adjacent the flange, a closure for the container including a relatively stiff reinforcing member and a plate 20 of relatively soft material covering the reinforcing member and having an inturned flange disposed opposite the first mentioned flange, and tension means engaging the closure and ring to urge the flanges toward each 25 other.
30. 6. In an evaporator for refrigerating apparatus, a cylindrical container forming a reservoir for liquid refrigerant having a flange formed out of the body of the container and projecting substantially at right angles to the axis of the container, a ring within the container adjacent the flange, a closure for the container including a relatively stiff reinforcing member and a plate 35 of relatively soft material covering the reinforcing member and having an inturned flange disposed opposite the first mentioned flange, tension members engaging the ring and passing through the closure, and screw-threaded caps for the tension members adapted to engage the plate with a sealing contact around the tension members.
40. 7. In an evaporator for refrigerating apparatus, a container forming a reservoir for liquid refrigerant, a removable closure for said container, a valve casing abutting said closure and a single tension means engaging the closure and valve casing to hold the casing in sealing engagement with the closure.
45. 8. Apparatus as defined in claim 7 wherein both the closure and valve casing are formed of relatively soft material, and the valve casing has a relatively sharp edge adapted to flow into sealing engagement with the closure 50 under the force exerted by the tension means.
90. 9. In an evaporator for refrigerating apparatus, a container forming a reservoir for liquid refrigerant, a removable closure for said container and a pair of valve casings abutting said closure and a single tension means for holding both casings to the closure. 70
95. 10. In an evaporator for refrigerating apparatus means forming a reservoir for liquid refrigerant, conduit connecting means engaging the container and a tension device for securing the connecting means to the reservoir, one of said means having a relatively sharp edge for causing said means to flow into sealing engagement with each other under the action of the tension device. 75
100. 11. In an evaporator for refrigerating apparatus, a container forming a reservoir for liquid refrigerant, a removable closure for said container, and a pair of conduit connections abutting said closure and a single tension means for holding both connections to the closure. 80
- In testimony whereof I hereto affix my signature.
